[57] CLAIM

The ornamental design for a punching and kicking bag for boxing and the martial arts, as shown and described.

DESCRIPTION

FIG. 1 is a front elevational view of a punching and kicking bag for boxing and the martial arts showing my new design;

FIG. 2 is a rear elevational view thereof;

FIG. 3 is a left side elevational view thereof;

FIG. 4 is a right side elevational view thereof;

FIG. 5 is a top plan view thereof and taken along line 5—5 of FIG. 1;

FIG. 6 is a bottom plan view thereof; and,

FIG. 7 is a bottom plan view of a modified embodiment of the design shown in FIGS. 1 through 6.

The broken line showing of a ceiling support in FIGS. 1 through 4 and the showing of a human figure in FIG. 1 is for illustrative purposes only and forms no part of the claimed design.

FIG. 2

FIG. 3

FIG. 4

FIG. 5

FIG. 6

FIG. 7
